US0D1104077S

(12) **United States Design Patent** (10) **Patent No.:** **US D1,104,077 S**
(45) **Date of Patent:** **** Dec. 2, 2025**

(54) **MACHINE LINKAGE**

(71) Applicant: **Caterpillar Inc.**, Peoria, IL (US)

(72) Inventors: **Terry Marlin Smith**, Clayton, NC (US); **Mathew Frana**, Bell Buckle, TN (US); **Steven James Juricak**, Peoria, IL (US)

(73) Assignee: **Caterpillar Inc.**, Peoria, IL (US)

(**) Term: **15 Years**

(21) Appl. No.: **29/915,476**

(22) Filed: **Oct. 31, 2023**

(51) LOC (15) Cl. **15-03**

(52) U.S. Cl.

USPC **D15/28**

(57) **CLAIM**

The ornamental design for a machine linkage as shown and described.

DESCRIPTION

FIG. 1 is a perspective view of a machine linkage showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the machine linkage which form no part of the claimed design.

1 Claim, 4 Drawing Sheets
